(57) **CLAIM**

The ornamental design for a convertible shoe, as shown and described.

DESCRIPTION

FIG. 1 is a perspective view of the convertible shoe, showing my new design;

FIG. 2 is a right-side elevation view thereof;

FIG. 3 is a left-side elevation view thereof;

FIG. 4 is a front view thereof;

FIG. 5 is a rear view thereof;

FIG. 6 is a front view thereof without shoe laces;

FIG. 7 is a top view thereof;

FIG. 8 is an exploded, right-side view thereof with front and rear portions removed; and,

FIG. 9 is a top view thereof with the front and rear portions removed from the upper for clarity of disclosure.

The broken lines depict environmental structure (e.g. shoe lace) and do not form a part of the claim.
